UNITED STATES PATENT OFFICE

HENRY P. FIELD, OF BERWICK, PENNSYLVANIA, ASSIGNOR TO AMERICAN CAR AND FOUNDRY COMPANY, OF NEW YORK, N. Y., A CORPORATION OF NEW JERSEY

CAR

Application filed July 27, 1928. Serial No. 295,751.

This invention relates to cars and more particularly to cars having drop bottoms composed of a plurality of hinged dumping doors and it is an object of this invention to provide an improved construction for a car of the class described. It is also an object of this invention to provide an improved latching mechanism for the doors of cars of the class described in which all the doors will be simultaneously operated by the engagement of a door operating arm with a track ramp.

In the drawings:

Figure 1 shows a central, longitudinal, vertical section of one-half of a mine car constructed in accordance with this invention, the section being taken as on the line 1—1 of Fig. 6;

Fig. 2 is a partial side elevation of the other half of the car to that shown in Fig. 1, part of one wheel being broken away to show the latch operating mechanism more clearly;

Fig. 3 is a broken top plan view of the mine car shown in Figs. 1 and 2, parts being broken away to show the latch operating mechanism more clearly;

Fig. 4 is a broken elevation of the car end shown at the left of Fig. 2, parts being broken away to show other parts more clearly;

Fig. 5 is a partial elevation of the car end shown at the right of Fig. 1;

Fig. 6 is a partial transverse section taken on the line 6—6 of Fig. 1;

Fig. 7 is a fragmentary longitudinal section taken on the line 7—7 of Fig. 6;

Fig. 8 is a fragmentary view in side elevation of another type of car constructed in accordance with this invention, parts being broken away to show other parts more clearly;

Fig. 9 is a partial vertical transverse section taken on the line 9—9 of Fig. 8; and

Fig. 10 is a partial horizontal section taken on the line 10—10 of Fig. 9.

As shown in Figs. 1 to 7, inclusive, of the drawings, a mine car constructed in accord-

ance with this invention comprises a body having channel shape longitudinal sills 1 connected at their ends by pressed Z end sills 2 joined to the longitudinal sills by angles 3. The longitudinal sills are carried upon bearings 4 and are provided with openings 6 through which extend the axles 8 mounted in the bearings 4 and upon which the wheels 10 are journaled. To the upper flanges of the longitudinal sills are secured the inclined side sheets 12 formed with wheel hoods 14 therein and braced from the sills 1 by braces 16. At their ends, the side sheets 12 are connected by end sheets 18 secured thereto by flanges 20.

The end sheets 18 are positioned inwardly 60 of the end sills 2 but connected thereto by braces 22. At one end the end sheet 18 is formed with an inwardly inclined portion 24 which is bent to form an outwardly projecting flange 26 while the other end sheet is 65 bent along its lower edge to provide an inwardly offset flange 28 extending parallel to the sheet.

At each end bumpers 30 are attached to the end sills 2 and at one end a coupler comprising a drawbar 32 is rigidly secured to the end sill 2 while at the other end a drawbar comprising jaws 34 having a cylindrical stem 36 is mounted in the opening 38 in the sill 2 and extends through an opening 39 in the 70 inclined portion 24 of the end sheet 18. The stem 36 is surrounded by a spring 40 confined between a collar or nut 42 secured on the stem 36 and a channel 44 which reinforces the end sill adjacent the opening 38. To 75 prevent interference with the operation of the spring 40 by the contents of the car the spring 40 is shielded by a pressed hood 46 attached to the adjacent end sheet 18.

Extending transversely of the car at the 80 axles 8 are hoods 48 comprising a plurality of sheets 49 and 50 secured to the sills 1 and side sheets 12 by angles 52. The sheets 49 and 50 are bent to provide vertically extending flanges 54 which are secured together, 85

outwardly extending inclined portions 55 and vertically extending portions 56 having outwardly offset vertically directed flanges 57 at their lower edges. The hoods 48 form cross ridges connecting the car sides.

6 The mine car illustrated in the drawings is shown as having a bottom comprising a door 58 which extends from one end sill to the adjacent axle, a door 59 which extends 10 between the two axles, and a door 60 which extends from the second axle to the adjacent or other end sill. Each door comprises a plate dished slightly towards its longitudinal center and provided with upwardly projecting flanges on all edges. The door 58 is pivotally connected to the end sill 2 by 15 hinges 62 and, in closed position, has its hinge edge flange projecting in back of the inclined portion 24 of the end sheet 18 and its free edge flange projecting in back of the offset flange 57 of the hood sheet 50. To 20 support the door 58 in closed position, the free edge of the door is provided with a plurality of projecting lugs or fingers 64 secured thereto and engaging on shoulders 65 formed 25 on latches 66 pivotally mounted at their upper ends on pins 67 inserted in openings in the vertical portion 56 of hood sheet 50 and in straps or brackets 68 attached to the inclined portion 55 of hood sheet 50. The 30 latches 66 are connected for simultaneous operation by a link 69 which extends between and is pivotally connected to both latches 66. Projecting upwardly from the link 69 is a 35 guide bracket 70 having an opening in which is loosely mounted one end of a spring rod 71 which has its other end mounted in a bracket 72 attached to the vertical portion 56 of hood sheet 50. Surrounding the rod 40 71 and confined between the brackets 70 and 72 is a spring 73 which holds the latches 66 in the latching position. Movement of the latches 66 under the influence of spring 73 is limited by the head 74 of the rod 71 engaging 45 the bracket 72 and a collar 75 fixed on the rod 71 engaging the bracket 70.

Doors 59 and 60 are hinged to the vertical portions 56 of the hood sheets 49 and have the flanges at their hinge edges extending 50 in back of the offset flanges 57 of the hood sheets 49. The flange at the free edge of door 59 extends in back of the flange 57 of a hood sheet 50 while the flange at the free edge of door 60 extends in back of the offset 55 flange 28 on the end sheet 18.

The door 59 is supported in closed position by latches the same as described in connection with door 58 supported from the hood sheet 50 and connected by a link 69 60 in the same manner while the latches 66 which support the door 60 are the same except for a difference in length in order to permit of attaching to the end plate 18 the brackets 68 which support one end of 65 the pins 67 which carry the latches 66, the

other ends of the pins 67 being carried on the end plate 18. The latches 66 for the door 60 are connected together by a spring 70 operated link 69 in the same manner as are the doors 58 and 59 but in the case of the door 60 the bracket 72 is attached to the end sheet 18. To prevent interference with the latches 66 of adjacent doors when the doors 75 are opened the plates forming doors 59 and 60 are punched upwardly as at 76 providing recesses in the under surfaces of the doors into which the adjacent latches 66 may project in case of excessive swinging of the doors 59 and 60.

To operate the doors there is provided a 80 shaft 77 journaled in bearing brackets 78 attached to the side sheet 12 and provided at one end with an outwardly projecting crank arm 79 which is guided in a yoke 80 and positioned to be operated by a track 85 ramp (not shown). Intermediate its ends the shaft 77 is provided with crank arms 81 which project downwardly and have their outer ends connected by links 82 to links 69, the links 82 engaging in slots 83 in the 90 links 69 so as to provide a lost-motion connection with the link 69. At its other end the shaft 77 is provided with a crank arm 84 which projects downwardly and is formed with slot 85 at its lower end. A link 86 mounted in an eye 87 attached to one of the latches 66 for the door 60 and in the slot 85 in crank arm 84 provides a connection between the shaft 77 and latches 66, the slot 85 in the crank arm 84 providing the 95 same lost motion as do the slots in the links 69. 100

When the arm 79 engages the track ramp, the arm 79 is raised by the track ramp as the car proceeds, rotating the shaft 77 and operating the cranks 81 and 84 to withdraw the latches 66 from the lugs 64 permitting the doors to drop and discharge. When the arm 79 leaves the track ramp the weight of the arm 79 and the springs 73 will return the latches 66 to their normal positions. When the doors are raised to their closed positions the lugs 64 will engage the beveled lower portions of the latches 66 forcing the latches to the right sufficiently to permit the lugs 64 to pass above the shoulders 65 whereupon the springs 73 will return the latches to their normal positions, placing the shoulders 65 beneath the lugs 64 and securing the doors in the closed position. During the operation of closing 115 the doors, the lost-motion connections between the links 69 and 82 for the doors 58 and 59 and between the link 86 and crank 84 for the door 60 permits of the latches 66 being operated by the lugs 64 without operating the shaft 77 and its crank arms. 120

In Figs. 8, 9 and 10, there is shown another type of car, in this instance a hopper car having a plurality of hoppers and comprising draft sills 101 which extend to and 125 130

are secured to the end slope sheets 103 by angles 105 and flanged side sills 107 to which are attached the hopper side sheets 109 and the Z-bar side posts 111. To the lower portions of the webs of the posts 111 and to the bottom flanges of the side sills 107 are attached transversely extending channels 113 positioned in oppositely arranged pairs with their flanges projecting outwardly and with the channels nearest the car ends or end channels connected to the draft sills 101 by flanged gussets 115. The channels 113 of each pair are spaced longitudinally of the car, the full extent of the hopper opening, and to the outer channel of each pair is attached the lower edge of the adjacent end slope sheet 103. The channels 113 and the hopper side sheets 109 define the hopper openings, the hopper side sheets being attached to the end slope sheets 103 by angles 117 and to the channels 113 by angles 119. The lower edges of the hopper side sheets are bent to extend vertically downwardly and are attached to flanged plates 121 which extend between the pairs of channels 113 and are secured thereto. Extending between the hopper side sheets 109 and having flanges at their ends secured to the hopper side sheets are slope sheets 123 which have their upper edges secured together and their lower edges secured to the center channels 113, the slope sheets 123 forming a cross ridge extending between the hopper side sheets 109.

To the end channel of one pair of channels 113 and to the center channel of the other pair are attached hinge brackets 125 to which doors 127, similar to door 58 of Fig. 1, are pivotally connected. To the other channels 113 of each pair of channels are attached brackets 129 in which are pivotally mounted the latches 131, the latches 131 engaging with lugs 133 on the doors 127 to retain the doors in closed position. The latches 131 on each channel 113 are joined for simultaneous operation by a link 135 pivotally connected to each latch 131. One latch 131 of each pair is connected by a link 137 to a crank arm 139 carried by a shaft 141 journaled in bearing 143 carried by the channels 113, the links 137 being pivotally connected to the latches 131 and having pin and slot connections with the crank arms 139.

To operate the latches 131 to release the doors 127, the shaft 141 is provided with a crank arm 145 which projects through a guide slot 147 in a plate 149 carried by the side posts 111 and extends sufficiently beyond the car side to be engaged by a track ramp (not shown). To insure the latches 131 being returned to door locking position, springs 151 are confined between brackets 153 carried by links 135 and brackets 155 carried by channels 113 and mounted upon pins 157 carried by the brackets 153 and 155.

The structure shown in Figs. 8 to 10 is operated in the same manner as the structure shown in the other figures, the arm 145 being raised by engagement with a track ramp as the car moves along and through arms 139 and links 137 operating the latches 131, against the resistance of the springs 151, to release the doors 127. When the arm 145 passes off the ramp, the springs 151 return the latches to locking position. When the doors are raised to closed position, the lugs 133 will engage the inclined lower faces 159 of the latches 131, shifting the latches 131 to permit the lugs 133 to pass the latches whereupon the springs 151 return the latches to engaging position beneath the lugs 133. During the closing of the doors the pin and slot connections between the links 137 and crank arms 139 permits movement of the latches 131 independently of the arms 139 and shaft 141.

What is claimed is:

1. In a car, a bottom dumping door, a plurality of latches for said door, said latches being pivoted for operation in the same direction in a vertical plane extending transversely of the car, a link connecting said latches and an operating shaft operatively connected to said latches. 90
2. In a car, a dumping door, a plurality of latches for said door, said latches being pivoted for operation in the same direction, a link extending transversely of the car connecting said latches, and an operating shaft extending longitudinally of the car operatively connected to said latches. 95
3. In a car, a bottom dumping door, a plurality of vertically hung latches for said door, a link connecting said latches, an operating shaft operatively connected to said latches and means operatively engaging said link for returning said latches to normal position. 100
4. In a car, a dumping door, a plurality of pivoted latches for said door, a link connecting said latches, an operating shaft, means operatively connecting said shaft and latches, said means permitting operation of said latches independently of said shaft, and means operatively engaging said link for returning said latches to normal position. 110
5. In a car, a dumping door, a plurality of latches for said door, said latches being pivoted for operation transversely of said car, an operating shaft extending longitudinally of said car and means operatively connecting said shaft and latches, said means permitting operation of said latches independently of said shaft. 120
6. In a car, a dumping door, a plurality of latches for said door, an operating shaft, and means operatively connecting said shaft and latches, said means permitting operation of said latches independently of said shaft. 125
7. In a car, a dumping door, a plurality of latches for said door, means connecting said 130

latches for simultaneous operation, an operating shaft, means operatively connecting said shaft and latches, said means permitting operation of said latches independently of said shaft, and means for returning said latches to normal position.

8. In a car, a dumping door, a plurality of vertically hung latches for said door arranged transversely of said car, means connecting said latches for simultaneous operation, a shaft operatively connected to said latches and means for returning said latches to normal position.

9. In a mine car having an axle, a hood over said axle, a dumping door for said car and latches for said door mounted on said axle hood to swing transversely of the car.

10. In a mine car having an axle, a hood over said axle, a dumping door for said car and pivoted latches for said door mounted within said axle hood for operation transversely of said car.

11. In a mine car having an axle, a hood over said axle, a dumping door for said car, pivoted latches for said door mounted within said axle hood, and means connecting said latches for simultaneous operation extending beneath said hood.

12. In a car, a plurality of dumping doors, a plurality of latches for each door, links connecting the latches of each door and operating transversely of the car, an operating shaft extending longitudinally of the car, and means operatively connecting said shaft to said latches.

13. In a car, a plurality of dumping doors, a plurality of pivoted latches for each door, means connecting the latches of each door, an operating shaft having a crank arm for each door, and means operatively connecting said crank arms to said latches.

14. In a car having a cross ridge, a dumping door for said car, pivoted latches for said door mounted beneath said cross ridge and means connecting said latches for simultaneous operation extending beneath said cross ridge.

15. In a car, a dumping door, a plurality of latches for said door, said latches being pivoted for operation transversely of said car, and an operating shaft extending longitudinally of the car and having a crank arm operatively connected to said latches.

16. In a car, a dumping door, a plurality of latches for said door, said latches being pivoted at their upper ends for operating transversely of said car, and an operating shaft extending longitudinally of said car operatively connected to said latches.

17. In a car, a plurality of dumping doors, a plurality of latches for each door, the latches for each door being connected and arranged transversely of the car, and an operating shaft extending longitudinally of the

car and having a crank arm for each door operatively connected to a latch therefor.

18. In a car, a plurality of dumping doors, a plurality of vertically hung latches for each door, the latches for each door being arranged transversely of the car and connected for simultaneous operation, and an operating shaft extending longitudinally of the car and having a crank arm for each door operatively connected to a latch therefor.

In witness whereof I have hereunto set my hand.
